CLAIM

The ornamental design for a fluid dispensing sponge
mop for use on a car, as shown and described.

DESCRIPTION

FIG. 1 is a perspective view of a fluid dispensing sponge
mop for use on a car showing my new design;

FIG. 2 is a side elevational view thereof;

FIG. 3 is a top plan view thereof;

FIG. 4 is a bottom plan view thereof;

FIG. 5 is an end elevational view thereof; and

FIG. 6 is an elevational view of the opposite end
thereof.
